UNITED STATES PATENT OFFICE.

ARTHUR J. BOYNTON, OF WINNETKA, ILLINOIS, ASSIGNOR TO H. A. BRASSET & COMPANY, OF CHICAGO, ILLINOIS, A CORPORATION OF ILLINOIS.

COKE BIN.

Application filed June 17, 1927. Serial No. 199,439.

This invention relates to an improvement in bins used for storing friable material such as metallurgical coke for use in blast furnaces and in other cases where the careful 5 sizing or grading of the material produced by screening or otherwise must be maintained to secure the most desirable results in the use of said material, and consists of the matters hereinafter described and more particularly pointed out in the appended claims.

The purpose and object of the invention may be most easily described and illustrated in connection with bins for the storage of coke for use in blast furnaces; but as will be 15 understood, its application is not limited thereto.

Coke after its manufacture is screened and segregated into lots or portions of graded size. It is then loaded into cars for transport to the blast furnace bins which should provide a large storage space. To get the benefit of the full storage capacity of bins of any kind, it is manifest that they must be substantially emptied before refilling. In 25 the case of the bins in question, however, this has not been practically feasible because in the charging or filling of an empty bin with coke, the shock due to the great drop from the car above it to the bin floor in the beginning and to the level of the surface of the coke until the bin is almost full, is so great, that there is considerable breakage of the coke. This breakage also results in segregation according to size, which increases 30 the bad effects following from breakage.

To overcome these objectionable results by reducing the drop of the coke, it has been the practice after the coke bin has been filled in the beginning, to supply enough cars for 40 transporting the coke to replace the coke in the bins by filling or charging from the cars at substantially the same rate that the coke is withdrawn from the bins. This in effect requires the bins to be practically always full 45 to the top. The bins thus act merely as a means for shortening the drop from the car to the bin discharge gate and the function of the bin as a store or reservoir for coke disappears. Costs required by the continuous 50 presence of operatives for unloading at the bins and by the continuous switching of the cars are increased as compared to cases when the bins function as stores or reservoirs.

The object of the present invention is to 55 provide a construction of bin in which the

full capacity of the bin as a store or reservoir may be utilized and the bin emptied or substantially emptied at intervals without danger of breaking the coke or other friable material from the shock of drop from the car which is unloading into the bin and without segregation according to size which results from such breakage.

The advantages of the invention will appear more clearly as I proceed with my specification.

In the drawings:—

Figure 1 represents a section through a bin made in accordance with my invention, in a plane transverse of the tracks above the bin.

Figure 2 represents a section through a bin of slightly modified construction wherein the plane of the section is parallel to the direction of the track above the bin.

Referring now to that embodiment of my invention illustrated in the drawings and particularly in Figure 1:—10 indicates a coke bin; 11, 11 indicate tracks for cars above the bin and in position to discharge thereinto; and 13, the girders which support the car tracks and bin. 14, 14 indicate the walls of the bin which walls are downwardly inclined and converge toward the discharge chute 15 and bin gate 15^a. As thus far described, the bin is of any usual or familiar construction.

16 indicates a plurality of spaced partition walls or diaphragms, each extending transversely of the bin and in substantial parallelism with one of the downwardly inclined walls 14, 14 thereof. Each partition wall 16 extends from the top or near the top of the bin but stops short of that wall of the bin to which it is not parallel. The several partition walls thus leave a passageway 17 between their bottom ends and the one wall 14 of the bin. This arrangement thus divides the bin into a plurality of inclined passageways 16^a running parallel to one inclined wall 14 of the bin from the top of the bin towards the other inclined wall 14, with each passageway 16^a communicating at its bottom end with the passageway 17 running parallel to the other wall 14 between the ends of said diaphragm 16 and said wall. All of the diaphragms, as are also the walls of the bin, are preferably inclined at angles slightly greater than the angle of repose of the material to be contained in the bin.

As a result of this construction, when a car is unloaded into an empty bin from either of the tracks 11, the coke discharged will fall with a short drop on one or the other of the 5 diaphragms or partition walls 16 and by a comparatively slow movement will run down said wall to the passageway 17 (between the ends of said diaphragms and the proximate wall 14 of the bin) until that passageway is 10 filled from the bin gate to the upper level of the bottom end of the passageway or passageways that are receiving the discharge of coke. The passageways themselves will then fill to the top of the bin. This method is followed 15 until all of the passageways 16^a (and thus the entire bin) are full to the top level of the bin. In this entire filling movement, the drop from the car to the diaphragms 16 is short as is also the drop from the ends of said diaphragms to the proximate wall of the bin defining the passageway 17, and the movement of the coke down the passageways is in all cases slow and easy. Thus both breakage 20 and segregation are avoided in filling the bin. 25 When the bin gate is open for the discharge of coke from the bin, the coke will first discharge from the passageway 16^a nearest the wall 14 to which it is parallel; it will next discharge from the passageway 16^a next above the first one and so on until all of the passageways 16^a have been depleted of their contents. 30 This will leave the passageway 17 from which the coke in the bin is last discharged.

In order to distribute the coke to the top 35 openings of all of the passageways 16^a, it may be preferred to use shuttle conveyors 18, 18 under each track 11, capable of both endwise and sidewise movement.

In Figure 2 I have shown a slightly modified form of the construction. In this case only one track 11^a is supported above the bin which has its length extending in the direction of the track. The diaphragm members instead of running in the direction of the 45 length of the track, are in this case arranged transversely of the track. 16^x indicates the said diaphragms which, as before, are arranged parallel to one of the downwardly inclined walls 14^x and provide passageways 16^a which 50 run from the top of the bin towards the sliding gates 15^x which close the discharge openings 15^y at the bottom of the bin, and towards the other downwardly inclined wall 14^x. Those of the diaphragms 16^x whose bottom 55 ends are beyond a point vertically above the bin gates terminates short of the other downwardly inclined bin wall 14^x, leaving a passageway 17^x between their bottom ends and said inclined wall and the planes of said 60 diaphragms terminate at points above the bin gates so as to leave a passageway or space 17^y above the bin gates.

The operation of filling the bin is substantially as described in the first case, the coke by

a short drop falling on the several partition 65 walls 16^x and running down them until arrested by one of the bin gates in the cases where said walls end above a bin gate or by the inclined wall 14^x providing the passageway 17^x in the case of the arrest of said diaphragm walls. 70

When the bin gates are opened in this case, the discharge will be first from the passageways leading directly to a bin gate. Afterwards the discharge will be from the passageway 17^x and from the several passageways 16^x connected therewith. 75

While in describing my invention I have referred to several details of mechanical construction and arrangement of parts, it is to be understood that the invention is in no way limited thereto except as may be pointed out in the appended claims.

I claim as my invention:

1. A bin adapted for the storage of friable 85 material, comprising oppositely inclined, downwardly converging walls, and a plurality of spaced partition walls substantially parallel to one inclined wall of the bin and extending transversely from the top of said bin 90 to the oppositely inclined wall.

2. A bin adapted for the storage of friable material, comprising oppositely inclined, downwardly converging walls, and a plurality of spaced partition walls extending 95 transversely of said bin, said partition walls being substantially parallel to one inclined wall of the bin and to each other and terminating short of the other inclined wall.

3. A bin adapted for the storage of friable 100 material, comprising oppositely inclined, downwardly converging walls, a plurality of spaced partition walls extending transversely of the bin and providing a plurality of passageways opening at one end towards the top 105 of the bin and at the other at points spaced from one wall of the bin, said partition walls being parallel to the other wall of the bin, and the two said walls and said partition walls being inclined at an angle somewhat greater 110 than the angle of repose of the material to be stored.

4. In a bin adapted for the storage of friable material, means providing a plurality of downwardly inclined passageways opening at 115 the top towards the top of the bin, one of said passageways being inclined at an angle to the other passageways which have their lower ends opening into said one passageway and functioning as a common exit passageway for 120 said other passageways, and the several passageways having walls inclined at an angle somewhat greater than the angle of repose of the material to be stored.

In testimony that I claim the foregoing as 125 my invention, I affix my signature this 14th day of June, A. D. 1927.

ARTHUR J. BOYNTON.
